ELECTRON FOCUSING SYSTEM

Willy Schroeder, Berlin, Germany, assignor to
 Telefunken Gesellschaft für Drahtlose Tele-
 graphie m. b. H., Berlin, Germany, a corpora-
 tion of Germany

Application May 5, 1939, Serial No. 271,861
 In Germany April 22, 1938

9 Claims. (Cl. 250—27)

The present invention relates to electron lens arrangement for electron-ray tubes. Ordinarily electron lenses are predicated upon the use of electromagnetic or electrostatic fields, steady or 5 invariable with time. In other words, unless an arrangement comprising a permanent magnet is concerned, they presuppose the provision of a D. C. source of supply. The use of such a source of current supply seemed indispensable with a 10 view to securing a position of the ray intersection point (cross-over) or electron image exhibiting time invariability. As a matter of fact, electron lens arrangements known in the prior art, when worked with A. C., would be unservable 15 for electron focusing. However, it is frequently desirable to operate with A. C. pure and simple, or more particularly with alternating current furnished from the conventional supply-line because this makes for simplicity of construction in general.

The invention discloses electron lens arrangements for electron rays which are adapted to be operated with A. C. without the use of D. C. and without the position of the focal point of 25 the electron ray being altered in any undesirable manner.

The invention shall now be discussed and explained by using as an instance an electromagnetic lens system.

As is well known, the focal length of a magnetic electron lens as by the field of an annular coil is inversely proportional to

$$\int_{-\infty}^{+\infty} H^2 dz$$

to the square of the current traversing the coil (where H is the field intensity in axis of coil, and z =coordinate in axial direction).

Providing two electromagnetic lens arrangements of fundamentally equal action, say, two annular coils of similar size and comprising equal numbers of turns, and if they are fed with two sine currents of like amplitude I_0 presenting a phase displacement of 90 degrees, that is, in quadrature relation, then their refractive power

$$D = \frac{1}{f}$$

is proportional to

$$50 \quad I_0^2 \sin^2 \omega t + I_0^2 \cos^2 \omega t$$

However, since $\sin^2 \omega t + \cos^2 \omega t$ is equal to 1, it follows that the refractive power of the magnetic lens under consideration is proportional to 55 I_0^2 , in other words, independent of the time.

This holds true particularly of the case that the lens fields of the two lens assemblies will not mutually influence each other to any essential degree.

In the case of coils comprising different turn numbers, ampere-turns in lieu of currents must be introduced in the above formula. The foregoing considerations hold good in an analogous manner also for coils of dissimilar forms and dissimilar diameters. But in such a case the currents of the coils must be so chosen that the focal distances determined by the effective values of the currents will be equal.

On the basis of these considerations, lens assemblies are obtained according to the invention 15 of the kind represented by the exemplified embodiments of the appended drawing in which

Fig. 1 shows a cathode ray tube which embodies my invention of two magnetic coils fed with alternating currents in phase quadrature, 20 while

Fig. 2 shows a modification of the embodiment of my invention in Fig. 1 in which three coils are used;

Fig. 3 shows two alternating currents in phase 25 quadrature in graphical form for explaining my invention;

Fig. 4 shows a further modification of the embodiment shown in Fig. 1;

Fig. 5 shows schematically an arrangement for 30 obtaining alternating currents in phase quadrature for use in the embodiments shown in Figs. 1, 2 and 4, and

Fig. 6 shows a modification of the embodiment of my invention, in which electrostatic 35 focusing systems are used.

In the simplest instance one may use coils of the same diameter and the same number of turns.

Fig. 1 shows an electron lens system which 40 comprises the coils M_1 and M_2 , coaxially positioned with respect to the cathode ray tube 21 having an electron gun 25 for producing a beam of electrons and having positioned a target member 23 on the interior face thereof. The target member 23 may conveniently be a fluorescent screen, for example, in a television receiving tube, or may be a mosaic electrode structure for a cathode ray television transmitting tube. It will be appreciated that deflecting systems, whether 45 electrostatic or electromagnetic, may also be provided for scanning the target member 23. Since these are well known in the art, they are not shown.

Through the coil M_1 by way of the terminals 55

5 and 5a is caused to flow an alternating current of sine form, that is, of a kind as shown by the graph S₁, Fig. 3. Through the coil M₂ by way of terminals 6 and 6a is passed also a 5 sinusoidal A. C. having the same frequency as the A. C. traversing coil M₁, while presenting a phase displacement angle thereto of 90 degrees, as shown by curve S₂ in Fig. 3. By the aid of the system comprising coils 1 and 2 it is possible to produce a sharp electron-optical image 10 or focus quite readily with alternating current in a way as above explained.

Fig. 2 illustrates another lens system which is adapted to be energized with A. C. This organization comprises three constituent coils, the central one of these coils indicated at M₄ containing the same number of turns as the two outer coils M₃ and M'₃ combined. The said central coil M₄ by way of terminals 7 and 7a is fed with an A. C. which has a phase displacement of 90 degrees in relation to the A. C. fed to the outer coils through the terminals 8 and 8a.

Inside the scope of the invention, more than two, say, n coils could be used, each of the coils 25 being traversed by the current of a phase of an n -phase supply line or network. The coils coordinated to the various phases could also be divided or split, and similarly as shown for the coils M₃ and M'₃, Fig. 2, they could be disposed 30 upon both sides of one or more coils which carry a current of different phase. So far as the relative spacing of the coils is concerned this should be kept in mind, as already pointed out, that the lens fields of the constituent coils should 35 not mutually react, for in the same measure as such mutual reaction occurs, the focus or picture sharpness will suffer, that is, be distorted, to a certain degree. In order that as satisfactory an image as possible may be secured, this 40 general rule will have to be observed that the distance of the coils in axial direction does not become less than $\frac{1}{3}$ the inside coil diameter. The coils may also be individually shielded to avoid interaction.

45 The arrangements as herein before described will generally be found serviceable for electron-optic imaging in which the rotation of the electron paths on traversing the various coils does not disturb, that is to say, for instance, in the 50 imaging of electron sources or apertures of diaphragms in picture scanning or picture re-creator tubes, in oscillographic tubes, or the like. If the rotation dealt with is such troublesome, for instance, in the imaging of a photo-cathode of 55 large area as used in what is known as picture converters or transducers, arrangements must be made so that the rotation of the image occurring at the frequency of the A. C. will be compensated. This is accomplished by causing the current of a certain phase to introduce rotational 60 actions which will neutralize one another.

An exemplified embodiment of this nature is 65 illustrated in Fig. 4, M₅ and M'₅ and M₆ and M'₆ designate the coils which are traversed by A. C. of a definite phase. All of the coils are wound in the same sense. The coils pertaining to one and the same phase, however, are traversed by current in contrary direction, in a way as indicated by the arrows. In this way, if the 70 intensities of the coil fields be properly chosen, perfect compensation of rotation is achieved.

In Fig. 5, I have shown schematically the 75 method of obtaining the alternating currents in phase quadrature. A source of alternating current 31 may be supplied directly to one of the

coils, such as M₁ through the terminals S₁. A phase shifting network or phase shifter such as well known in the art may be connected in parallel with the source of alternating current 31 to shift the alternating current 90 degrees, the 5 phase shifter being represented diagrammatically by the block 33, since these are well known in the art. The output of the phase shifter is then supplied through the terminals S₂ to the second of the two coils M₂ in Fig. 1. 10

Instead of lens assemblies which comprise electromagnetic lenses, it would, of course, also be feasible to use electrostatic lenses operated in a corresponding manner with alternating potentials; the electrostatic lenses being formed by the 15 field set up between two or more lens electrodes as shown in Fig. 6.

In Fig. 6 is shown the electron gun 41 for producing a beam of electrons and the lens electrodes 43, 45, 47 and 49 enclosed within an envelope 51. Suitable leads are provided for supplying one alternating current potential S₁ to the electrodes 43 and 45, while an alternating current potential in quadrature to S₁ is supplied from the source S₂ to the electrodes 47 and 49. There 20 is thus provided alternating electrostatic fields 25 which are in phase quadrature.

Having described my invention, what I claim is:

1. The method of focusing a beam of electrons 30 which comprises producing an alternating focusing magnetic field having axial symmetry about the beam of electrons, and producing a second alternating focusing magnetic field longitudinally displaced from the first produced field and in phase quadrature with the first produced field, said second produced field having axial symmetry with the electron beam.

2. The method of focusing a beam of electrons 40 which comprises producing an alternating focusing magnetic field having axial symmetry about the beam of electrons, and producing a second alternating focusing magnetic field of a magnitude equal to the magnitude of the first produced field longitudinally displaced from the first produced field and in phase quadrature with the first produced field, said second produced field having axial symmetry with the electron beam. 45

3. The method of focusing a beam of electrons 50 which comprises producing an alternating focusing field having axial symmetry about the beam of electrons, and producing a second alternating focusing field longitudinally displaced from the first produced field and in phase quadrature with the first produced field, said second produced field having axial symmetry with the electron beam. 55

4. The method of focusing a beam of electrons 60 which comprises producing an alternating focusing field having axial symmetry about the beam of electrons, and producing a second alternating focusing field of a magnitude equal to the magnitude of the first produced field longitudinally displaced from the first produced field and in phase quadrature with the first produced field, 65 said second produced field having axial symmetry with the electron beam.

5. The method of focusing a beam of electrons 70 which comprises producing an alternating focusing electrostatic field having axial symmetry about the beam of electrons, and producing a second alternating focusing electrostatic field longitudinally displaced from the first produced field and in phase quadrature with the first produced field. 75

duced field, said second produced field having axial symmetry with the electron beam.

6. The method of focusing a beam of electrons which comprises producing an alternating focusing electrostatic field having axial symmetry about the beam of electrons, and producing a second alternating focusing electrostatic field of a magnitude equal to the magnitude of the first produced field longitudinally displaced from the first produced field and in phase quadrature with the first produced field, said second produced field having axial symmetry with the electron beam.

7. A cathode ray tube system comprising means for producing a beam of electrons, means for producing an alternating focusing magnetic field having axial symmetry about the beam of electrons, and means for producing a second alternating focusing magnetic field longitudinally displaced from the first produced field and in phase quadrature with the first produced field, said second produced field having axial symmetry with the electron beam.

8. A cathode ray tube system comprising means

for producing a beam of electrons, means for producing an alternating focusing magnetic field having axial symmetry about the beam of electrons, and means for producing a second alternating focusing magnetic field of a magnitude 5 equal to the magnitude of the first produced field longitudinally displaced from the first produced field and in phase quadrature with the first produced field, said second produced field having axial symmetry with the electron beam. 10

9. A cathode ray tube system comprising means for producing a beam of electrons, means including an annular coil for producing an alternating focusing magnetic field having axial symmetry about the beam of electrons and means including 15 a second annular coil for producing a second alternating focusing magnetic field longitudinally displaced from the first produced field and in phase quadrature with the first produced field, said second coil being longitudinally displaced 20 from said first named coil by a distance greater than one third the annular diameter.
